[57] **ABSTRACT**

An accelerometer for attachment to the shaft of a conventional-type golf club and which when in use occupies a position adjacent the head of the club. The device includes a spring loaded rod mounted for retractable movement within a housing. The rod has teeth along one longitudinal edge to provide a rack and an indicia speed measuring scale along a diametrically opposite longitudinal edge. A latching and ratcheting pawl is mounted on the housing and is operatively coordinated with the teeth of the rack. The end of the rod which projects outward of the housing is provided with a detachable weight which enables the user to determine the proper weight needed in the head of the club to achieve maximum club head speed.

Fig. 2

GOLF CLUB ATTACHMENT FOR DETERMINING OPTIMUM CLUB HEAD WEIGHT

This invention relates to an improved accelerometer provided with clips or the like which are so constructed and oriented that it is capable of being readily but reliably clipped on the shaft of a golf club and is equipped with self-contained facilities which function in a manner to enable the user of the club to measure and ascertain the club head speed required for an acceptably reliable maximum power swing.

More specifically the concept has to do with a club swing power metering attachment which is readily attachable to and detachable from the shaft of the golf club which is being tested and which is herein designated as an accelerometer and which, as a result of trial and error experimentation enables the user of the club to not only measure and see the results of his swing but to satisfactorily ascertain the weight which he needs in the head of the club to evaluate and determine upon the weight which is deemed to be necessary and needed to repeatedly achieve maximum club head speed. It is submitted that by using the herein disclosed device and properly altering the weight in the base of the club head it is possible to accomplish maximum club head speed and, as a result thereof to gradually acquire the maximum power required when the desired swing has been perfected.

To the ends desired the attachment is such in the construction that the coordinating and conjointly performing structural features combine for accurately determining the proper weight that should be used in the club head to achieve maximum speed for the individual who is, at the time, using the club.

The idea of measuring the speed of a golf club head with a view toward finding out how fast it is being swung or to convert the noted speed in relation to yardage for the golf ball when struck is admittedly old and well known. For example and for background purposes the reader may desire to take note of a golf club attachment shown in U.S. Pat. No. 2,543,722 granted to Frederick W. Hetzel and which teaches the idea of measuring the centrifugal force of a golfer's swing. Another example which has to do with a yardage meter attachment is shown in U.S. Pat. No. 2,986,937 granted to Loyal H. Chapman. Then, too, and for further background information wherein a spring-loaded plunger in a case or housing is shown is set forth in U.S. Pat. No. 3,561,272 granted to Grady B. Davis.

An object of the present invention is to structurally, functionally and in other ways to improve upon prior art adaptations utilizing force-measuring facilities and, in so doing, to provide a simple, practical and economical adaptation the primary purpose of which is for determining the proper weight that should be used in the club head to achieve the maximum speed possible for a given individual.

The maximum speed in conjunction with the maximum weight that can be utilized in a swing at maximum speed is deemed to be the envisioned goal of every golfer and, as is believed to be evident in the present disclosure, is a significant object of the invention herein comprehended.

Briefly the attachment is constructed to provide a club head accelerometer and which comprises a vertically elongated hollow housing having forward and rearward ends. A spring-loaded rod is mounted for projectable and retractable reciprocation in the housing.

This rod has teeth along one edge or surface which constitute a rack and has one lengthwise face provided with a graduated maximum speed measuring scale. The rod has a rearward enclosed end and a forward portion normally projecting through and beyond the coacting forward neck-like end of the housing and is equipped with an attachable and detachable as well as changeable weight. A latching and ratcheting pawl is externally and operatively mounted on the forward end portion of the housing and is operatively coordinated with the teeth of the rack. Suitable means is provided for detachably mounting the housing on the shaft of the golf club adjacent to the head and parallel with the shaft.

These together with other objects and advantages which will become subsequently apparent reside in the details of construction and operation as more fully hereinafter described and claimed, reference being had to the accompanying drawings forming a part hereof, wherein like numerals refer to like parts throughout.

FIG. 1 is a view in perspective showing a conventional golf club and showing, what is more significant, the club head accelerometer and how it is applied for use.

FIG. 2 is a view on a suitably enlarged scale with parts in section and elevation showing the component parts and how they are individually constructed and structurally related for best results.

In FIG. 1 the golf club is conventional and is denoted at 4 and comprises a shaft 6 having a handgrip 8 at the upper end and a conventionally constructed head 10 at the lower end.

With reference now to the views of the drawing and particularly with respect to FIG. 2 it will be evident that the aforementioned housing is denoted by the numeral 12, said housing being cylindrical in transverse cross section and of a uniform cross section throughout the main or body portion and defining an enclosed hollow space 14. The forward end is gradually reduced in cross section or dimension and provides a guide neck 16 terminating in a restricted opening 18. The rearward or upper end portion of the cylindrical housing is open and is appropriately screw threaded as at 20 to accommodate the screw threaded rim 22 of a closing cap 24. Appropriate attaching and retaining spring clips are provided at 26 and are located near the upper and lower end portions and adjoined by attaching shank portions 28. The manner in which the clips are applied to the shaft is brought out in FIG. 1. Manifestly these clips position the device so that it is parallel with the shaft and above the level of the head with the neck end facing the head 10.

A spring-loaded rod is mounted for projectable and retractable reciprocation in the housing 12. This rod is denoted, generally stated, by the numeral 30 and has a circular abutment or appropriate shoulder means 32 on the upper or rearward end portion 34. This means serves to accommodate the uppermost convolution or coil 36 on the properly enclosed and concealed coil spring 38. The forward or lowermost convolution or coil is denoted at 40 in FIG. 2 and rests on the enclosed tapering collar 42. This collar is shaped to fit within the confines of the neck as is clear from FIG. 2. One longitudinal edge portion of the rod is provided with a multiplicity of suitably shaped and proportioned teeth 44 which conjointly provide the desired rack. The diametrically opposite surface portion is provided with graduations 46 defining a force-measuring scale 48. The

spring tension is such that the forward end portion of the rod or plunger projects beyond the opening 18 of the neck where (shown in FIG. 2) the rod is provided with a reduced screw-threaded stud 50. This stud is screwed into a screw-threaded socket 52 provided therefor in an attachable and detachable ball-like weight 54. The latching and ratcheting pawl means is exteriorly and operatively mounted on the housing and is operatively coordinated with the teeth of the rack. This means is denoted by the numeral 56 and comprises a leaf spring having a major portion which is longitudinally bowed as at 58. The forward or tip end is appropriately dimensioned and constitutes a detent 60 which is cooperable with the teeth 44 of the aforementioned rack. A median bowed portion 62 is secured by a rivet or the like 64 to the housing in the locale shown in FIG. 2. The free and suitably bent outward end portion 66 is fashioned into and provides a manually actuatable detent applying and releasing finger piece.

The measuring plunger is shown in its normal retracted position in FIG. 2 but actually the spring tension and plunger construction might be such that the weighted ball would be in a normal position proximal to or abutting the neck opening 18 (not shown).

It can be mentioned in passing that the device as shown and described lends itself to practical use for both right-hand and left-hand golfers.

This device is clipped or mounted on the golf club in the area of the club head as shown in FIG. 1 in such a manner and position that the spring-loaded weighted plunger is allowed to project automatically when the necessary impetus is initiated by the applied centrifugal forces.

The manner in which the latching and ratcheting means 56 functions is believed to be self-evident from the views of the drawing. The construction and coordination of the individual parts is also believed to be clear. The scale on the plunger is visible when the plunger is extended and can be read to determine the maximum speed achieved. It follows that by use of this attachment or device and altering the weight in the base of the golf club head, it is possible to achieve a maximum power swing for a given individual.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention. 7

What is claimed as new is as follows:

1. For use when one is desirous of determining the acceptably ideal weight needed in the head of a golf club for best results, a club head accelerometer comprising a vertically elongated hollow housing having forward and rearward ends, a spring-loaded rod mounted for projectable and retractable reciprocation in said housing, said rod having teeth along one edge providing a rack and having one lengthwise face provided with a graduated maximum speed measuring scale, said rod having a rearward enclosed end and a forward end portion normally projecting through and beyond the coacting forward end of said housing and equipped with a weight, a latching and ratcheting pawl exteriorly and operatively mounted on the forward end portion of said housing and operatively coordinated

with the teeth of said rack, and means carried by and for detachably mounting said housing on the shaft of a golf club adjacent the aforementioned head.

2. The club head accelerometer defined in and according to claim 1, and wherein said rod constitutes a plunger, the forward end of said rod being screw-threaded and providing a weight mounting stud, said weight being detachable and interchangeable and having a screw-threaded socket into which said stud is screwed in a manner to secure said weight in its usable position.

3. The club head accelerometer defined in and according to claim 1, and wherein said latching and ratcheting pawl comprises a leaf spring having a major forward portion longitudinally bowed with its forward terminal end fashioned into a tooth ratcheting detent, a median portion riveted to a prescribed exterior surface portion of said housing, and a free curvate rearward end portion spaced outwardly from said surface portion and providing a manually actuatable detent applying and releasing finger piece.

4. The club head accelerometer defined in and according to claim 1, and wherein said housing is cylindrical in transverse cross section, the forward end being gradually reduced in cross-sectional dimension and providing a guide neck for that portion of the rod which is slidingly mounted therein.

5. A club head accelerometer for attachment to the headed end portion of the shaft of a conventional-type golf club comprising a vertically elongated hollow cylindrical housing open but provided with an attachable and detachable closing cap at its rearward end, the forward end being gradually reduced in cross-sectional dimension and fashioned into and providing a guide neck, a rod having a major body portion and rearward end portion confined for operation in the hollow portion of said housing, the terminal part of said rearward end portion having a fixed head-like abutment, the forward end portion having a reduced screw-threaded stud equipped with an attachable and detachable ball-shaped weight of predetermined heaviness, said rod having teeth along one longitudinal side providing a rack and having a graduated maximum speed measuring scale along a diametrically opposite side, a coil spring confined for operation in the hollow portion of said housing and surrounding said rod and having a rearward end retentively engaging said head-like abutment and a lower end resting on a thrust shoulder provided within the confines of said neck, a latching and ratcheting pawl exteriorly and operatively mounted on the forward end portion of said housing and operatively coordinated with the teeth of said rack, and means carried by and for detachably mounting said housing on the shaft of a golf club adjacent the aforementioned head.

6. The club head accelerometer defined in and according to claim 5, and wherein said latching and ratcheting pawl comprises a leaf spring having a major forward portion longitudinally bowed with its forward terminal end fashioned into a tooth ratcheting detent, a median portion riveted to a prescribed exterior surface portion of said housing, and a free curvate rearward end portion spaced outwardly from said surface portion and providing a manually actuatable detent applying and releasing finger piece.
